UNITED STATES PATENT OFFICE.

FRANÇOIS LUCAS, OF MUNSON'S, PENNSYLVANIA.

SNOW-SWEEPER.

SPECIFICATION forming part of Letters Patent No. 536,637, dated April 2, 1895.

Application filed December 27, 1894. Serial No. 533,093. (No model.)

To all whom it may concern:

Be it known that I, FRANÇOIS LUCAS, a citizen of the United States, residing at Munson's, in the county of Clearfield and State of Pennsylvania, have invented certain new and useful Improvements in Snow-Sweepers; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to snow-sweeping machines and more particularly to that class of snow-sweepers commonly known as track cleaners which aim to keep railway tracks unincumbered with snow.

20 The object is to provide a sweeper of the class described which will more effectually sweep the road bed and rails and which at the same time will deposit the swept snow on either side of the track.

25 A further object is to provide means whereby any snow that may freeze to the operating or adjacent parts will be quickly melted so that no clogging will result.

With these objects in view my invention 30 consists of a rotary brush adapted to sweep the snow into a hopper, and a device operating with a reciprocating movement within the hopper to expel the snow therefrom.

It further consists in suitable devices for 35 removing snow or ice which may freeze to the operating parts and tend to hinder them.

In the accompanying drawings; Figure 1, represents a bottom view of my complete invention; Fig. 2, a side elevation thereof, and 40 Fig. 3, a sectional side elevation, showing the direction of the brushes and the course of the swept snow.

45 A represents the body of an ordinary flat-car mounted upon the axles 1 which are provided with the usual wheels 2. The sides 3 of this car extend forward as shown at 4 to provide a suitable structure wherein the sweeping and scraping mechanisms operate.

Around the top of the car A extends a ridge 50 5, thus providing a suitable box into which ballast may be placed to give proper traction to the wheels of the car. Depending from

the extensions 4 are two sets of hangers 6, and 7, respectively, and the side walls 4^a of the sweeping chamber. These hangers are 55 securely bolted to the said extensions and are provided at their lower extremities with journal boxes 8, and 9 respectively which are adapted to receive the journals 10 and 11 of the respective rotary parallel brushes 12 and 13. To serve all purposes these brushes may be of the usual construction, but I sometimes prefer to affix the bristles to longitudinal strips or sections 14 which are in turn attached by suitable devices to the body of the 60 brush. This latter method possesses advantages over the usual construction in that it allows of the easy withdrawal of any section should the brush need repairing. The brushes 10 and 11 are placed in such relation one to 65 the other as to leave but a slight space between the respective sets of bristles on the two brushes. A web or wall 15, formed preferably of sheet metal, extends across the space intervening the respective extensions 70 4, being affixed to the lower edges thereof, and is formed at its rear end into an elongated hopper 16 open at either end. This web is provided with a series of perforations 75 17, and any suitable material, such, for instance, as salt may be placed upon the top of the wall or web when the machine is in operation to filter through and melt any snow or ice which may cling to it and the adjacent parts of the device. A series of scraping 80 disks 18 connected by a rod 19, are adapted to play longitudinally within the hopper 16 to eliminate from and deposit on either side of the railway track the snow and ice which is swept 85 into the said hopper by the brushes 12 and 13 90 which precede it. Sprockets 20 and 21 are keyed to the respective axles 1, and a sprocket chain 22 operating over them adds greater power to both axles; and to one extremity of the forward axle is affixed another sprocket 95 23. A shaft 24, journaled in boxes 25, is provided with two sprockets 26 and 27 respectively, and has also keyed thereon a cog gear 28. Motion is imparted to the shaft 24 through the medium of a short sprocket chain 29 which 100 runs over the sprockets 23 and 26. One of the journals 10 of the brush 12 extends beyond its respective journal box 8 to receive a sprocket 30, and a sprocket chain 31 operating over

the sprockets 27 and 30 communicates motion to the said brush when the machine is in operation. On one of the extended journals 11 of the brush 13 is keyed a pinion 32 which meshes with the cog gear 28, and it and hence the brush 13, receive motion from this gear. By this construction it will be seen that the brush 13 is adapted to revolve at a greater peripheral velocity than the brush 12 for reasons which will be hereinafter set forth. The rod 19 and hence the scraping disks 18 are operated through mechanism which will now be described. To one of the axles 1 is keyed a crank 33 to which is attached, by means of the wrist-pin 34, a pitman 35. This pitman is connected to a bar 36 which operates through a guide or hanger 37 and is provided with a rack 38. This rack meshes with a mutilated pinion 39 journaled in a U-shaped bracket 40 affixed to the side 3 of the car. A pair of toggle-levers 41 and 42, the one projecting from the pinion 39 and rigidly affixed thereto, and the other pivotally connected to the rod 19, afford a connection between the said pinion 39 and the scraping device so that when the pinion is rocked by the reciprocation of the bar 36 when the wheels 2 revolve, the scraping disks will travel longitudinally within the hopper 16.

Having thus fully described my invention I will now proceed to describe its operation.

When it is desired to clean the snow from the railroad track, the snow-sweeper is coupled to the front of a locomotive and pushed by the same. As the wheels revolve motion is imparted through the sprocket chains and the gearing to the rotary brushes which, owing to the peculiar arrangement of the said chains and gearing, will revolve in opposite directions, as shown by the arrows in Fig. 3 of the drawings. By an inspection of this figure it will be seen that the forward brush revolves in a clock-wise direction, and the rear brush, in a counter-clock-wise direction. By this construction, as the machine advances, the snow is drawn in under the forward brush, where it strikes the rear brush and owing to the direction and rapidity of revolution of the latter, the snow is thrown upward, as shown by arrows, against the web above the brushes and from thence deflected into the hopper. In the meantime the scraping disks have been at work owing to the movements of the toggle-levers and devices that connect them with the car axle. As the snow falls into the hopper, the reciprocation of the scrapers therein forces it out at either end of the said hopper, depositing it on either side of the railway track. If any snow should freeze to the web above the brushes, the salt issuing through the perforations therein will cause it to melt thus preventing the machine from becoming clogged, which might occur were this feature of the invention omitted.

I do not limit myself to the precise construction herein shown and described, but consider myself entitled to all such variations

as might suggest themselves to a skilled mechanic and come within the spirit and scope of the invention.

Having thus described my invention, what I claim as new, and desire to secure by Letters Patent, is—

1. In a snow sweeper, the combination with a hopper, and a discharging device adapted to reciprocate therein, of a rotary brush adapted to throw snow into the hopper.

2. In a snow sweeper, the combination with a hopper, and a discharging device adapted to reciprocate therein, of parallel rotary brushes adapted to throw snow into the said hopper.

3. In a snow sweeper, the combination with a hopper, and a discharging device adapted to reciprocate therein, of a pair of rotary brushes adapted to revolve in opposite directions and to throw snow into the hopper.

4. The combination of sweeping brushes, a hopper, and a series of disks operating within the hopper.

5. The combination with a pair of rotary brushes revolving in opposite directions, of a hopper, and a series of disks operating within the hopper.

6. In a snow sweeper, the combination with a pair of rotary parallel brushes adapted to revolve in opposite directions, of a hopper, and a series of scraping disks operating within the hopper to discharge therefrom the snow which is thrown therein by the brushes.

7. In a snow sweeper, the combination with a hopper, of forward and rear rotary brushes adapted to revolve in opposite directions, the forward brush revolving in such direction that the snow will be drawn in under it and thence lifted into the hopper by the combined action of the two brushes.

8. In a snow sweeper, the combination with a hopper and a discharging device adapted to reciprocate therein, of a pair of parallel rotary brushes adapted to revolve in opposite directions to throw snow into the hopper.

9. In a snow sweeper, the combination with a hopper, and a pair of rotary brushes adapted to revolve in opposite directions and at different speeds, of a discharging device adapted to reciprocate within the hopper.

10. In a snow sweeper, a sweeping chamber formed of side walls and a web extending between the said side walls, which is bent at one end into a depending hopper.

11. In a snow sweeper, a receptacle formed into a depending hopper at one end and provided with perforations in its bottom, whereby salt or like material, adapted to melt snow and ice, placed therein, may filter through.

12. In a snow sweeper, the combination with a sweeping brush, of a receptacle provided with a perforated bottom, the said receptacle being placed in such relation to the sweeping brush as to allow its contents to filter through the perforated bottom onto the brush.

13. In a snow sweeper the combination with the scraping disks operating within the hopper.

per, of mechanism connecting the said disks to the axle of the car, whereby when the 5
sweeper is in operation, the said disks will be caused to operate within the said hopper to expel the snow therefrom.

14. In a snow sweeper, the combination with a hopper of a discharging device adapted to reciprocate within the hopper, and mechanism connecting the said discharging device 10 with the axle of the car, whereby when the

sweeper is in operation the said discharging device will operate within the hopper to discharge the snow therefrom.

In witness whereof I affix my signature in presence of two witnesses.

FRANÇOIS LUCAS.
